UNITED STATES PATENT OFFICE.

JOHN C. McKEOWN, OF CHICAGO, ILLINOIS.

TRUSS.

1,417,929.

Specification of Letters Patent. Patented May 30, 1922.

Application filed September 20, 1919. Serial No. 325,243.

To all whom it may concern:

Be it known that I, JOHN C. McKEOWN, a citizen of the United States, and resident of Chicago, in the county of Cook and State 5 of Illinois, have invented a new and useful Truss, of which the following is a specification.

This invention relates to trusses and relates particularly to trusses comprising a 10 continuous, bowed upper chord and a lower chord, both built up from timbers forming different layers, said chords being connected by suitable bracing.

The object of the invention is to provide 15 a truss of this type which will combine the features of adequate strength, simplicity of construction and economy of manufacture. To this end, my improved truss comprises the various features, combination of features and details of construction hereinafter 20 described and claimed.

In the accompanying drawings, in which my invention is fully illustrated,

Figure 1 is a side view of a truss embodying my invention;

Figure 2 is an enlarged sectional view thereof on the line 2—2 of Fig. 1; and

Figure 3 is an enlarged sectional view thereof on the line 3—3 of Fig. 2.

Referring now to the drawings, 1 designates the bowed top chord of the truss and 2 the bottom chord thereof, both of which are built up from continuous layers of plank or other timbers rigidly connected together 35 to form unitary structures.

As regards my present invention, the specific construction of the top and bottom chords of my improved truss is not material and both of said chords may be of any 40 desired or approved construction. Desirable forms of chords are those shown and fully described in my co-pending application for improvements in trusses, filed in the Patent Office on or about September 15, 45 1919, Serial No. 323,831, to which reference is made for a detailed description thereof.

The ends of the top chord 1 are rigidly connected to the bottom chord 2, preferably by means of straps 3 secured to said bottom 50 chord, and extend around the ends of said top chord 1, said top chord being provided with shoulders at its ends which abut against the intermediate sections of said straps 3.

Said chords 1 and 2 are rigidly connected

at intervals throughout their length by means of tie rods 4 and are held in desired spaced relation by means of struts or stanchions 5 inserted between the adjacent sides of said chords, the tie rods 4 preferably 60 extending through holes formed lengthwise through said struts or stanchions.

For simplicity and cheapness of manufacture, the struts or stanchions 5 preferably consist of two longitudinal sections designated 5¹ and 5², the holes through said stanchions which receive the tie rods 4 being formed by grooves 6 formed in the face of the thicker stanchion member 5¹ which contacts with the strut or stanchion member 70 5², the difference in the thickness of said members 5¹ and 5² being substantially equal to the depth of the grooves 6, whereby said grooves will be formed entirely in the thicker sections of said struts or stanchions. 75

After the stanchion sections 5¹, 5² have been assembled between the chords 1 and 2 with the tie rods 4 extending through the holes formed therein by the grooves 6, the sections of said struts or stanchions are 80 rigidly connected by bolts or other suitable means inserted therethrough at desired intervals, and the ends of said struts or stanchions are confined in recesses 7 formed transversely in the adjacent sides of the 85 top and bottom chords 1 and 2.

The heads of the rods 4 and the nuts threaded therethrough preferably bear against washers or plates 8 inserted over said rods and adapted to bear directly 90 against the outer sides of the top and bottom chords, said plates or washers 8 on the upper chord at opposite sides of the center being thickened at their outer edges to provide a flat bearing for the heads of said tie 95 rods, or the nuts threaded thereto, as the case may be.

A particular advantage of the truss of the present application is that the tension rods 4, being encased within the struts or 100 stanchions 5, will be protected thereby in case of fire and thus will not be heated to a degree which will weaken them—at least not in the initial stages of the fire.

A further advantage of my improved 105 truss is that, owing to the relatively large unobstructed spaces between the struts or stanchions 5, trusses of this particular type admit of ornamentation by means of grilles or scroll work inserted in the open spaces of 110

said trusses, which renders them particularly desirable for church work and the like where ornamental effects are desired.

I claim:—

- 5 1. In a truss, the combination of a bowed top chord and a bottom chord, means for rigidly connecting the ends of the top chord to the bottom chord, and bracing for said truss comprising only tie rods which connect said top and bottom chords, stanchions inserted between said top and bottom chords, said stanchions being provided with holes formed lengthwise through the same through which said tie rods extend, said stanchions comprising a plurality of connected longitudinal sections of different thicknesses, and the holes therein being formed by grooves formed in the connected faces of the thicker sections thereof and the open sides of said grooves being closed by the thinner sections of said stanchions, substantially as described.
- 10 15 20 2. In a truss, the combination of a bowed top chord and a bottom chord, means for

rigidly connecting the ends of the top chord to the bottom chord, and bracing for said truss comprising only tie rods which connect said top and bottom chords, stanchions 25 inserted between said top and bottom chords, said stanchions being provided with holes formed lengthwise through the same through which said tie rods extend, said stanchions comprising a plurality of connected longitudinal sections of different thicknesses, and the holes therein being formed by grooves formed in the connected faces of the thicker sections thereof and the open sides of said grooves being closed by 30 the thinner sections of said stanchions, respectively, substantially as described.

In testimony that I claim the foregoing as my invention, I affix my signature this 15th day of September, 1919.

JOHN C. McKEOWN.
